Primary Examiner — Cathy Anne MacCormac(74) *Attorney, Agent, or Firm* — Lerner, David, Littenberg, Krumholz & Mentlik, LLP(57) **CLAIM**

The ornamental design for an automated ball-throwing apparatus, as shown and described.

DESCRIPTION

FIG. 1 is a perspective view of an automated ball-throwing apparatus according to my new design;

FIG. 2 is a right side view thereof;

FIG. 3 is a left side view thereof;

FIG. 4 is a back view thereof;

FIG. 5 is a front view thereof;

FIG. 6 is a top plan view thereof; and,

FIG. 7 is a bottom plan view thereof.

The broken lines shown in the drawings represent portions of the automated ball-throwing apparatus that form no part of the claimed design.
